UNITED STATES PATENT OFFICE

WILLIAM A. BENDER AND HUGO G. LOESCH, OF ROCHESTER, NEW YORK, ASSIGNEES,
BY MESNE ASSIGNMENTS, TO GENERAL FOODS CORPORATION, A CORPORATION OF
DELAWARE

MEDICINAL PREPARATION

No Drawing.

Application filed October 27, 1924. Serial No. 746,214.

This invention relates to medicinal preparations and, more particularly, to medicinal oil preparations adapted to be taken internally as laxatives, one object of the invention being to provide an improved preparation of this nature having the bland and nonirritating purging qualities characteristic of castor oil, combined with the lubricating qualities of a mineral oil, such as a petrolatum liquidum, and thus adapted to be frequently used without the constipating and other unfavorable after effects of castor oil. Another object is to provide a homogeneous, stable compound of the character described comprising a mixture of castor oil and mineral oil in the form of a permanent emulsion. A further object is to provide a simple and practical method for producing a stable, homogeneous mixture of normally immiscible oils, such as castor oil and mineral oil, for affording the product desired.

To these and other ends the invention resides in certain improvements and combinations of parts, all as will be hereinafter more fully described, the novel features being pointed out in the claims at the end of the specification.

The invention comprises in the present instance a mixture of castor oil and petrolatum liquidum in a stable, homogeneous emulsion. Castor oil, as is well known, is the blandest and least irritating purge, but a disadvantage in its use resides in the fact that it tends to product hemorrhoids if used constantly and also in the fact that its frequent use or even a single dose is generally followed by constipation, so that the dose must be rapidly increased in size to be effective. This militates against the frequent use of castor oil in the treatment of constipation.

Mineral oil is now sold on the market under various names and is used internally and regularly as a lubricant to promote normal bowel activity. It has been found that a combination of this oil with castor oil affords a compound which combines the beneficial properties of both oils without the unfavorable after effects of castor oil, and that such normally immiscible oils may nevertheless be combined in a stable, homogeneous compound

in any suitable proportions adapted to the results desired.

Castor oil and mineral oil, however, do not mix freely and it is impossible by any of the usual methods to prepare a mixture of the two oils that will not separate. Thus if quantities of these two oils be placed in the same container and agitated or shaken, they refuse to mix and shortly separate into definite layers, the heavier castor oil sinking to the bottom and the mineral oil separating out and collecting above it. These two oils are thus substantially immiscible in one another. It has been found, however, that a homogeneous mixture of these two oils in any proportions can be effected by emulsification. The emulsions of these oils in any suitable relative proportions blend perfectly to form a stable, homogeneous emulsion, the word "emulsion" being used herein in the sense of what is known as an "oil-in-water" emulsion.

The emulsification of oil involves the very fine dispersion of the oil in water, generally effected or stabilized through the use of some colloid. Gum acacia has been generally used in the pharmaceutical art as an emulsifying agent although other such agents have been and are used. The emulsification of oil through the use of jellifying pectin as an emulsifying agent is described and claimed in the Letters Patent to Robert Douglas and Hugo G. Loesch, No. 1,625,641, dated April 19, 1927, for emulsification of oils, and the same method of emulsification is preferably employed in the present invention.

Such emulsification of an oil can be quickly obtained by adding slowly with constant stirring and mixing with one part, say, of a 5% solution of pectin in water, 1 to 4 or more parts of the oil according to the character of the emulsion desired, whereupon the emulsion immediately begins to form on the first addition of the oil and continues to do so and to thicken to a firm stable emulsion. A more or less concentrated solution of pectin may be employed and the emulsion may be thinned with water as conditions may require.

The combining of the ingredients can be carried out in several ways. Thus, for exam-

ple, the emulsion of each oil can be prepared as described and the emulsions then mixed together. Or, the two oils can be run simultaneously in separate streams into the emulsifying agent with constant stirring, the final product being a homogeneous stable emulsion of both oils. One oil, however, can be mixed with the emulsifying agent and the second oil then added and emulsified in this emulsion. It is also practical to continuously stir the two oils in a container to form a crude temporary mixture which is run into the emulsifying solution and emulsified. The resulting stable homogeneous emulsion can be flavored and sweetened to taste if desired.

Thus the emulsification method described affords a stable mixture of castor and mineral oils in which the two are permanently and homogeneously blended and remain so as the product combines the beneficial effect of both oils with the great additional advantage that the presence of the mineral oil prevents the constipating and other evil after-effects of the castor oil and thus permits the compound to be used frequently or in small daily doses in the treatment of constipation without injurious results. The castor oil, being finely subdivided in the emulsion, is quickly digested and effects its purging action, while the non-digestible mineral oil retains in its emulsified condition its full mechanical value as a lubricant in its passage through the alimentary canal. The relative degree of the lubricating and purging effects of this compound can be controlled by varying the relative proportions of the two oils used in the emulsion which may be flavored and sweetened to taste if desired.

We claim as our invention:

- 40 1. A pharmaceutical preparation comprising a homogeneous mixture of castor oil and a mineral oil in suitable proportions with an emulsifying ingredient.
- 45 2. A homogeneous mixture of castor oil and petrolatum liquidum in suitable proportions and in emulsion form with jellifying pectin as a stabilizing ingredient.
- 50 3. The process of preparing a stable homogeneous mixture of castor oil and a mineral oil consisting in combining the said oils by emulsification with a suitable emulsifying ingredient.
- 55 4. The process of preparing a stable homogeneous mixture of castor oil and petrolatum liquidum consisting in combining the said oils in suitable proportions by emulsification with jellifying pectin as an emulsifying ingredient.
